UNITED STATES PATENT OFFICE.

CONSTANTINE D. JIANAS, OF KANSAS CITY, MISSOURI.

COUNTER-SERVICE DEVICE.

Application filed November 22, 1923. Serial No. 676,273.

To all whom it may concern:

Be it known that I, CONSTANTINE D. JIANAS, a subject of the Kingdom of Greece, residing at Kansas City, in the county of 5 Jackson and State of Missouri, have invented certain new and useful Improvements in Counter-Service Devices, of which the following is a specification.

My invention relates to a service device 10 for use at soda fountains and the like, and my object is to provide an attractive as well as useful device of this character wherein accessories commonly used around a soda fountain, such as spices, straws, 15 menu cards, etc., are assembled for convenience of the patrons.

In order that the invention may be fully understood, reference will now be had to the accompanying drawings, in which:

20 Fig. 1 is a side elevation of the device.

Fig. 2 is a plan view of the device.

Fig. 3 is a vertical sectional view of the device.

25 Fig. 4 is a horizontal section on line IV—IV of Fig. 3.

In carrying out the invention, I employ a pedestal 2 having a socket 4 in its upper portion to receive the lower end of a crystal or other elongated jar 6 open at its upper 30 end to receive straws A, such as are customarily employed at soda fountains. The jar 6 is secured in position in the socket 4 by means of a band 8 secured to the top of the pedestal by suitable means such as 35 pins 10. The band 8 is made in two sections and projects into a peripheral groove 12 in the lower portion of the jar 6 to reliably hold the same upon the pedestal 2.

Spaced above the groove 12 is another 40 peripheral groove 14 formed in the jar 6 between two peripheral beads 16 to receive an annulus 18, provided with shelves 20 having depressions 22 to hold accessories, such as salt and spice receptacles B and C.

45 Spaced above the groove 14 is another groove 26 formed by peripheral beads 28 to receive an annulus 30 from which brackets 32 project. Each bracket 32 is provided at its outer end with a rack 34 to hold a menu card. Each rack 34 is of 50 V-form in plan view, the two wings 36 thus provided having a ledge 37 extending across their lower portions and upon which a menu card may rest, the wings 36 serving as a 55 support for the back of the menu card.

The upper portion of each rack 34 is

provided with a clamp 38 for holding a bill of fare or menu card in addition to the one held by each rack. Each clamp 38 comprises a fixed jaw 40 integral with or otherwise secured to the associate bracket 34, a movable jaw 42, springs 44 for pressing the jaw 42 towards the jaw 40, and set screws 48 threaded into the fixed jaw 40 and extending freely through the movable jaw 42 60 to yieldably hold the latter upon the former. The tension of the springs 44 is regulated by proper adjustment of the set screws 48. Each movable jaw 42 has a reinforcement 50 at its upper portion, which serves as a 65 handle whereby said jaw 42 may be lifted from the jaw 40 to admit the upper edge of a bill of fare or menu card.

Referring again to the jar 6 it will be noted that its bottom 52 is dome shaped 70 as shown by Fig. 3. This serves to hold the straws A in step formation, so that a single straw may be easily grasped and lifted from the jar after removal of the lid 54. The lid 54 is provided with a knob 56 whereby it may be removed from or placed upon the jar 6. The knob 56 has a stem 58 extending downwardly from the lid 54 and provided with a pendant cable 60, preferably, in the form of a chain to 80 which the upper end of a coil spring 62 is connected. The spring 62 which coacts with the cable 60 in yieldably holding the lid 54 on the jar 6, is connected at its lower end to a bolt 64 extending through the 85 respective bottoms of the jar 6 and a tube 68 and provided with a shoulder 66 engaging the bottom of said tube 68 to secure the same to the bottom of the jar. A rubber or other yieldable washer 70 is interposed 90 between the bottom of the jar and the lower end of the tube 68 while a similar washer 72 is interposed between the bottom of the jar and a nut 74 threaded on the lower end of the bolt 64 to protect said bottom 95 from injury when the nut 74 is screwed up. The tube 68 encloses the cable 60 and spring 62, so that the straws A will not come in contact therewith when being placed within or removed from the jar 6. 100

From the foregoing description it is apparent that I have provided a device upon which a number of accessories may be assembled for the convenience of patrons, 110 and while I have shown and described the preferred construction, combination and arrangement of parts, I reserve the right to

make such changes as properly fall within the spirit and scope of the invention as claimed.

Having thus described my invention, 5 what I claim and desire to secure by Letters Patent, is:

A device of the character described consisting of a jar arranged to support exteriorly disposed shelves and brackets and 10 having a dome shaped bottom, a lid to said

jar, a tube open at its upper end and closed at its bottom, a bolt securing the bottoms of the jar and said tube together and projecting into the recess formed by the dome shaped bottom of the jar, a cable connected 15 to the lid and extending down into said tube, and a coil spring secured at its ends to said cable and said bolt.

In testimony whereof I affix my signature.

CONSTANTINE D. JIANAS.
